(57) **CLAIM**

The ornamental design for an smart phone case, as shown and described.

DESCRIPTION

FIG. 1 is an isometric view of the front cover of the smart phone case, which embodies my design;

FIG. 2 is a front view of the front cover of the smart phone case;

FIG. 3 is a rear view of the front cover of the smart phone case;

FIG. 4 is a right side view of the front cover of the smart phone case;

FIG. 5 is a left side view of the front cover of the smart phone case;

FIG. 6 is a top plane view of the front cover of the smart phone case;

FIG. 7 is a bottom plane view of the front cover of the smart phone case;

FIG. 8 is an isometric view of the back cover of the smart phone case;

FIG. 9 is a rear view of the rear cover of the smart phone case;

FIG. 10 is a front view of the rear cover of the smart phone case;

FIG. 11 is a right side view of the rear cover of the smart phone case;

FIG. 12 is a top plane view of the rear cover of the smart phone case;

FIG. 13 is a bottom plane view of the rear cover of the smart phone case; and,

FIG. 14 is an illustrative view of a smart phone showing my new design in a position of use.

The broken line showing of the smart phone in FIG. 14 is for illustrative purposes only and forms no part of the claimed design.
